UNITED STATES PATENT OFFICE.

CARL AUGUST OSTERBERG, OF BOSTON, MASSACHUSETTS.

PIANOFORTE-FLANGE.

SPECIFICATION forming part of Letters Patent No. 634,474, dated October 10, 1899.

Application filed December 12, 1898. Serial No. 698,964. (No model.)

To all whom it may concern:

Be it known that I, CARL AUGUST OSTERBERG, of Boston, in the county of Suffolk and State of Massachusetts, have invented a new and useful Improvement in Pianoforte-Flanges, of which the following, taken in connection with the accompanying drawings, is a specification.

My invention relates to the peculiar construction and arrangement of a flange for pianofortes, the exact nature of which may be best understood by reference to the specification and drawings, the object being to so construct a flange for pianoforte-actions that each one is adjustable and will admit of removing the part that is pivotally attached to it by simply turning a clamping-screw. These objects I attain by means of the mechanism shown in the accompanying drawings, in which—

Figure 1 is a perspective view showing a rail having one of my flanges attached, also showing in connection a hammer-butt. Fig. 2 is a cross vertical section showing the rail and flange. Fig. 3 is a perspective view showing one member of the flange. Fig. 4 is a perspective view showing the second or spring member of the flange.

In the drawings I have illustrated my invention as it appears when used in connection with the hammer-butt, although it will apply equally well to the jack or to any pivotal joint in connection with a pianoforte-action.

In the drawings, R represents the rail, to which the flanges for supporting the hammer-butts H are attached. These flanges F K are secured to the rail R by screws T. Each flange has two parts or members F and K, especially shown in Figs. 3 and 4. The member F has a large hole H for the reception of an annular rib D, made on the member K. This rib D is shown in Fig. 2 as entering the hole H. The object of this construction is that the two members F and K shall be accu-

rately held in place one upon the other. The screw T passes through both of the members, as shown in Fig. 2. The neck F' of the member F of the flange has a groove G, preferably V-shaped, for the reception of the pivot-pin 50 P. The neck K' of the spring member is bent or folded back upon itself, as shown in Figs. 2 and 4, for the purpose of obtaining a firmer bearing for the head of the clamping-screw S. The pin P, which acts as a pivot for the 55 hammer to swing upon, is held firmly in place by the clamping action of the spring member K.

When it is desired to detach the hammer, the user has only to slacken the clamping-screw S. This action will allow the spring member K to yield sufficiently to admit the pin P to slip upward between the upper parts of the members F and K, and thus allowing the hammer-butt to be removed. The hammer-butt may be replaced and securely held by tightening up the screw S, it not being necessary to draw the pin from the hammer-butt.

I claim—

In a pianoforte-action an adjustable flange 70 consisting of two detachable members, one having a groove adapted to receive the pivot-pin of the hammer-butt, and a large orifice to engage with an annular rib projection from the second member; a second member 75 adapted to coact with the first member adapted to hold the said pivot-pin of the hammer-butt and having an annular rib adapted to engage with the said orifice of the first member, and a clamping-screw adapted to hold 80 the said members together, substantially as and for the purpose set forth.

In testimony whereof I have signed my name to this specification, in the presence of two subscribing witnesses, on this 22d day of 85 October, A. D. 1898.

CARL AUGUST OSTERBERG.
